UNITED STATES PATENT OFFICE.

HARRY WALLACE LAWRENCE, OF TRENTON, NEW JERSEY.

LAMP-RECEPTACLE.

No. 864,426.

Specification of Letters Patent.

Patented Aug. 27, 1907.

Application filed August 20, 1906. Serial No. 331,292.

To all whom it may concern:

Be it known that I, HARRY WALLACE LAWRENCE, a citizen of the United States, residing at Trenton, in the county of Mercer and State of New Jersey, have 5 invented certain new and useful Improvements in Lamp-Receptacles, of which the following is a full, clear, and exact description.

This invention relates to lamp receptacles and pertains particularly to a form of receptacle to be used 10 with lamp clusters, electric signs, banks of incandescent lamps, and all purposes where lamps are assembled into groups and electrically connected with one another in series or multiple.

The principal object of the invention is to provide, 15 as an article of manufacture, a complete lamp receptacle in the form of the usual threaded shell, the threaded shell in this case constituting the housing and supporting framework of all the parts. In other words I provide in the form of a threaded shell, a unitary structure 20 embodying all the parts of a complete socket and the terminal connections for an incandescent lamp. This article of manufacture, complete in itself, is, however, assembled with an outside supporting base in use. The outside base or supporting block may be furnished 25 with the receptacle proper or sold separately, or may be made specially to suit any special or particular requirements. The last mentioned condition is the one most likely to occur in practice, where, for example, it is desired to have incandescent lamps in the columns 30 and molding and paneling of a room.

The invention therefore lies in the receptacle as an article of manufacture, for which purposes it is complete in itself. In use, however, the receptacle is always contained in a separate block or base.

35 With the above and other objects in view, the invention consists of the features of construction herein-after described and claimed.

In the drawings:—Figure 1 is a sectional view showing the application of receptacles embodying the principles of my invention; Fig. 2 is a detail sectional view showing the various parts of the receptacle in position ready to be assembled; Fig. 3 is a sectional view showing the complete receptacle. Fig. 4 is an external, bottom plan view of the annular block or support 40 shown in Fig. 1, with a group of my receptacles mounted therein, and Fig. 5 is a detail sectional view on the line 5—5 of Fig. 4.

In order to make the necessary circuit connections with any form of incandescent lamp, a special receptacle is required, comprising a socket to receive the lamp and terminal clips for connection with the circuit wires.

On account of insurance regulations, and other requirements of practice, the usual receptacle is a large 55 and rather cumbersome structure of porcelain and brass, not well suited to the purposes of interior decoration.

In carrying out the present invention I do away with this form of receptacle and substitute in lieu thereof a structure having all its essential characteristics, that is, the lamp socket and terminals, but which is 60 practically no larger than the base of an ordinary incandescent lamp.

With a receptacle of this form it is possible to group the lamps in any way desired for interior decoration, and yet no unsightly parts will be visible to mar the 65 ornamental effect.

Referring now to the drawings, in which like parts are indicated by the same reference sign, 1 denotes a threaded shell of which the internal surface 2 is adapted to receive an ordinary incandescent lamp, while 70 the external surface 3, being necessarily also threaded, is adapted to be screwed into a cavity of corresponding form. The lower edge of the shell is flanged inward as shown at 4 and is perforated with a comparatively large aperture 5.

75 6 indicates a button of insulating material which is centrally apertured at 7 and has a portion 8 of a diameter corresponding to the hole 5 and adapted to project therethrough. The main portion of the button 6 is of a diameter to closely fit within the shell 1 and shoulder against the flange 4 thereof.

80 9 indicates an insulating washer having a central hole 10 of a size to fit over the reduced portion 8 of the button 6. The thickness of the washer is such that when the parts are assembled, the lower surface 85 of the washer lies an appreciable distance from the end of the button, as clearly shown in Fig. 3.

11 indicates a metallic plate preferably circular, and having a threaded hole 12. This hole is adapted to receive a screw 13 which is passed through the various parts and which in turn finally receives the nut 14 at its extremity.

90 For the purpose of making the terminal connections, special metallic clips are ordinarily used, although ordinary copper wire can be employed if desired.

95 In the drawings I have indicated sheet metal clips 15 and 16, clip 15 having an aperture 17 corresponding to the diameter of the reduced portion of the button 6, while the clip 16 has a hole 18 of sufficient size to receive the screw 13. The parts are assembled with the clip 15 in contact with the flange 4 of the threaded shell, and the clip 16 between the plate 11 and the nut 14. Screw 13 therefore forms the central stud contact for the lamp and the clip 16 the circuit terminal therefor. The clip 15 is in direct connection 100 with the threaded shell and constitutes the terminal therefor.

105 It will be observed that while the electrical connections are thus efficiently made, all of the parts of opposite polarity are separated by an adequate partition of insulating material. The reduced portion 8 of the button 6 cooperates with the insulating washer 9

to separate the clip 15 at all points from the plate 11 and the central screw. But the presence of this insulating partition does not impair the clamping of the metallic parts on account of the fact that a space is left between the button 6 and the plate 11, as above stated.

In use it is merely necessary to obtain a block or support 19, recessed with suitable cavities 20 formed to receive the threaded shells 1. For temporary purposes, the support 19 need not be either fireproof or insulating in character, but for interior and permanent insulations, it is best to have the support 19 of porcelain. In this way the insurance regulations are complied with as fully as by the use of any standard receptacle.

In Fig. 1 I have illustrated the clips 15 connected to the threaded shells while the clips 16 are in connection with the central stud contacts. This would be the arrangement for ordinary multiple wiring. In Figs. 2 and 3 the clips 15 and 16 are bent so as to be capable of connection with a threaded shell and with a central stud contact at their respective ends. This arrangement would be the one employed for series wiring. In case the lamps are distributed in such a way that their axes are in different and non-parallel planes, the various clips 15 and 16 can always be bent so as to accommodate any arrangement.

The clips 15 and 16 being pivoted to or flexibly connected to the different receptacles, the latter are capable of being mounted upon a common support in any desired relative arrangements or positions. The

circuit wires will be respectively connected to any pair of the clips 15, 16, in any suitable way.

Having described my invention, I claim:—

1. In a lamp receptacle of the class described, a threaded shell having an internal flange, a button received in said shell and having a reduced portion projecting through said flange, an insulating washer adapted to fit over the reduced portion of said button, a screw passed through said button and a plate received on said screw and a nut threaded on said screw to clamp said plate upon said washer.

2. In combination with a base of any suitable character having threaded recesses therein, a lamp receptacle exteriorly threaded to fit said recesses, the corrugations of said exteriorly threaded portions constituting interiorly the threads of the lamp receptacle, said lamp receptacle having a central stud contact supported by the receptacle and movable therewith, and means for making the terminal connections.

3. In combination with a base of any suitable character having threaded recesses therein, a threaded shell constituting a lamp receptacle, a central stud contact supported by said shell insulated therefrom and removable therewith, and means for making the terminal connections with said shell and contact.

4. In combination with a base having threaded recesses therein, a threaded shell constituting a lamp receptacle and formed to be screwed into said recesses, said shell having an insulating button contained therein and wholly supported thereby, and a central stud within said button and wholly supported thereby.

In witness whereof, I subscribe my signature, in the presence of two witnesses.

HARRY WALLACE LAWRENCE.
